UNITED STATES PATENT OFFICE.

MATHEW J. BURKEL AND LOUIS P. FOSNOT, OF AURORA, ILLINOIS.

VALVE-SPRING-LIFTING DEVICE.

Application filed July 11, 1921, Serial No. 483,685.

To all whom it may concern:

Be it known that we, MATHEW J. BURKEL and LOUIS P. FOSNOT, citizens of the United States, and residents of Aurora, county of Kane, and State of Illinois, have invented certain new and useful Improvements in Valve-Spring-Lifting Devices; and we do hereby declare that the following is a full, clear, and exact description thereof, reference being had to the accompanying drawings, and to the letters of reference marked thereon, which form a part of this specification.

This invention relates to improvements in valve spring lifting devices and consists of the matters hereinafter described and more particularly pointed out in the appended claims.

The object of the invention is to produce a tool of the kind, the jaws of which are always maintained in parallel relation and which is capable of a wide range of opening movement of the lifting jaws combined with a minimum span of movement of the operating handles and which is capable of a maximum of lifting power with a minimum of length of tool. Another object of the invention is to provide a tool of the kind in which the jaws are so arranged that the tool is readily capable of use in close quarters when parts adjacent the valve spring to be operated upon stand in the way of direct access to the spring.

In addition the novel tool comprises a minimum of parts which may be produced with great economy both as to cost of manufacturing the parts and as to the facility and ease of assembly and possesses other advantages which will appear as we proceed with our specification.

In the drawings:—

Fig. 1 is a side elevation of the improved valve spring lifter shown with its lifting jaws substantially closed;

Fig. 2 is a top plan view of the same;

Fig. 3 is a longitudinal sectional view—shown with the jaws open—in a plane indicated by the line 3—3 of Fig. 2;

Fig. 4 is a transverse section in a plane indicated by the line 4—4 of Fig. 3;

Fig. 5 is a perspective view of one of the operating hand levers.

Referring now to that embodiment of the invention illustrated in the drawings: 10—10 indicate the opposed jaw members, each provided with a bifurcated jaw 11 adapted to

embrace the valve stem and having a flat part 12 for engagement beneath the valve spring, with a semi-circular upright shoulder 13 spaced back from the edge of the flat part for embracing the peripheral body of the spring.

The body 14 of each jaw member is a straight bar, made hollow, as shown, with depending side flanges 15. The jaw proper 11 extends at an angle to the length of the body 14, so that the tool may be inserted for engagement with the valve spring at one side of and back of any obstruction that may interfere with direct access. The jaw, if desired, may of course be made to extend directly in line with the body 14. The jaw members, when made as last described, may be stamped by means of the same forming die and even when made as shown in full lines may be fabricated from the same blanks—two forming dies however being required.

The jaw members are connected together and maintained in parallel relation by means of a lazy tongs 16, the elements 17, 17 of which have fixed pivotal connection at their forward ends to the bodies 14 of the respective jaw members 10, by means of transverse pins 18, 18 fixed in the flanges 15 of said bodies, and movable pivotal connection at their rear ends with said bodies by means of transverse pins 19, 19 carried by said rear ends and mounted to slide in longitudinal slots 20 formed in said flanges. The elements of the lazy tongs are themselves pivoted together by means of a pin or rivet 22.

23, 23 indicate the lever handle members. Said members are in form like the levers of a pair of pliers. Each is a flanged bifurcated bar, the bifurcations 24 of which embrace the sides of the bodies 14 of the jaw members as shown in Figure 2. The bifurcations 24 have like fulcrum extensions 25, 26 which are pivoted together on a transverse pin 27 and the short arms 28 of the levers are pivoted on the transverse pins 18, 18 which connect the jaw members to the forward ends of the lazy tongs 16. The fulcrum pin 27 of the levers is located back of the pivot pin 22 of the lazy tongs.

To retain the jaws open in one or more positions, we provide a latch bar 29. Said bar is pivoted back of the fulcrum pin 27 on transverse pin 30 fixed in one lever and is provided with a series of ratchet teeth 29a adapted for engagement with a transverse

bar 31 fixed in the other lever,—the latch bar extending up through a suitable slot 32 in the lever body immediately back of the jaw members 10 and being preferably provided

5 with a forwardly bent knurled finger piece 33 for use in releasing the latch. A coiled spring 34 connecting the latch bar to the lever on which it is pivoted acts to normally hold it in engagement with the bar 31.

10 The levers are made alike so that a single set of tools is required to make both. To this end, one of the fulcrum extensions 26 is offset towards the median plane of the lever so that it may receive, in a plane adjacent 15 to it, the fulcrum extension 25 of the other lever which is not thus offset.

From an inspection of the drawings, it is apparent that the power applied to the handles is greatly multiplied when applied by the short lever arms of said levers to open the jaw members and that this is made possible in a construction wherein the greatest span between the lever handles is not greater than will easily come within the 25 grip of a hand of ordinary size. Again, by reason of the location of the fulcrum 27 back of the axis pin 22 of the lazy tongs, the power is applied by the short arms of the levers in lines at an angle closely approximating a right angle to the length of 30 the jaw members, so that a maximum component of the actual power exerted by said arms is applied in opening said jaw members. Thus a tool of comparatively short 35 length is capable of great lifting power under the grip exerted by one hand.

In the manufacture of the tool as heretofore has appeared only three blanks are required (eliminating the latch and spring). 40 So that it manifestly may be made very cheaply. Other advantages will be evident to those familiar with the art.

We claim as our invention:—

1. A valve lifting device comprising two 45 parallel jaw members, hand levers fulcrumed together between said jaw members near the rear ends of said jaw members and having short arms operatively connected to the front ends of said jaw members, means independent of said levers flexibly connecting said jaw members and adapted to maintain them in parallel relation, and means for automatically locking said jaw members in several, varied, open positions.

50 2. A valve lifting device comprising two parallel jaw members, a lazy tongs connecting said jaw members and adapted to maintain them in parallel relation, and hand levers having integral fulcrum extensions pivoted together at a point between

said jaw members and back of the axis of said lazy tongs, said hand levers having short arms pivotally connected to the front ends of said jaw members.

55 3. A valve lifting device comprising two parallel jaw members, a lazy tongs connecting said jaw members and adapted to maintain them in parallel relation and hand levers fulcrumed together between said jaw members at a point back of the axis of said lazy tongs and having short arms pivotally connected to the front ends of said jaw members and means for automatically locking said jaw members in several, varied 70 open positions.

75 4. A valve lifting device comprising two parallel jaw members, a lazy tongs connecting said jaw members and having fixed pivotal connection therewith at their forward ends and slot and pin connections therewith at their rear ends, and hand levers having integral fulcrum extensions pivoted together at a point between said jaw members and back of the axis of said lazy tongs, said hand levers having short arms pivotally connected to said jaw members at points coaxial with the pivotal connection of said lazy tongs.

80 5. A valve lifting device comprising two parallel jaw members, a lazy tongs connecting said jaw members and having fixed pivotal connection therewith at their forward ends and slot and pin connection therewith at their rear ends, hand levers fulcrumed to one another intermediate said jaw members 85 at the rear of the axis of said lazy tongs and having short arms pivotally connected to said jaw members at points coaxial with the fixed pivotal connections of said lazy tongs, and an automatic latch member adapted to 90 lock said jaw members at various distances apart.

95 6. A valve lifting device comprising jaw members, lazy tongs and operating levers, each jaw member being a flanged bar having a bifurcated jaw formed at one end, and each lever being a flanged bar bifurcated at its forward end to embrace an associated jaw member, and the flanges having fulcrum extensions, one of which is offset from the 100 plane of the flange.

105 In testimony that we claim the foregoing as our invention, we affix our signatures in the presence of two witnesses, this 1st day of July, A. D. 1921.
